UNITED STATES PATENT OFFICE.

PIETER DE LANGE AND ROBERT AERNOUT BARON VAN LYNDEN, OF UTRECHT, NETHERLANDS, ASSIGNORS TO NAAMLOOZE VENNOOTSCHAP DE NEDERLANDSCHE THERMOTELÉPHON MAATSCHAPPIJ, OF UTRECHT, NETHERLANDS, A CORPORATION OF THE NETHERLANDS
THERMIC TELEPHONE.

1,243,048.

Specification of Letters Patent. Patented Oct. 16, 1917.

Application filed November 4, 1915. Serial No. 59,629.

To all whom it may concern:

Be it known that we, PIETER DE LANGE and ROBERT AERNOUT BARON VAN LYNDEN, both subjects of the Queen of the Netherlands, and residing at Utrecht, in the Netherlands, have invented certain new and useful Improvements in Thermic Telephones, of which the following is a specification.

This invention relates to thermic telephones and particularly to the heat conductors employed therein. Such conductors are fixed in a support by passing them through holes in said support. According to our invention those parts of the heating wires which are in said holes are provided with flattened portions which firmly hold them in said holes. This makes a reliable connection between the support and the wires and the wire is not liable to become loose as otherwise may occur when the holes of the support are widened even to a small extent. Such widening of the holes may be caused, for instance, by increases of temperature or by shrinking. A good connection between the support and the heating wire is particularly important with respect to etching, because, when manufacturing on a large scale, it is possible to obtain equal sound emitting lengths only if the wires are firmly held in their supports, as otherwise they will not project from said supports for the same distance, and consequently the lengths for which the wires are etched will not be the same for all wires.

Reference is to be had to the accompanying drawings in which an example of our invention is illustrated. Figure 1 is a sectional elevation and Fig. 2 a plan view of a support holding a heating wire according to our invention, Figs. 3 and 4 are a front and lateral view of the heating wire, respectively. All the figures are drawn to an enlarged scale.

Both branches of the arc-shaped heating wire 10 are passed through holes 11 of a support 12 made of insulating material, such as Vulcan fiber. The arc of the wire projects for a certain distance over the support, as clearly shown in Fig. 1. The ends 13 of the wire branches are bent at an angle and forced into a groove 14 provided on the lower surface of support 12.

The branches of the wires are, at some distance above their bent ends 13, provided

with flat parts 15 which may be produced in any convenient manner, as by tongs, etc. These flattened and laterally extended parts 15 act as cutting edges when the wire is passed through the round holes 11 (enlarging such holes laterally at and above the portions 15 as indicated in Fig. 1), so that the wire becomes clamped or wedged in the holes and is securely held in position.

The wire 10 is drawn into the holes of the support by means of an apparatus which is so constructed as to exactly determine the length of wire projecting from the support. The apparatus may also serve to bend the feet 13 and to force them into groove 14.

Obviously, instead of being flat as shown the parts 15 may be of other cross-sectional shape. It is only essential that they are not circular in cross section and that part of their cross section extends beyond the round portion of the wire. The cross section of parts 15 will, in every instance, depend on the cross sectional form and size of the holes 11.

We claim:

1. A heat conductor for thermic telephones, provided with end portions of uniform cross section and having adjacent to said end portions, portions extending laterally beyond the cross section of said end portions.

2. A heat conductor for thermic telephones, provided with end portions, laterally-enlarged portions adjacent to said end portions, and a loop connecting the inner ends of said enlarged portions.

3. A heat conductor for thermic telephones, provided with end portions of uniform cross section and having, adjacent to said end portions, portions extending laterally beyond the cross section of said end portions, and a looped portion connecting the inner ends of said laterally-enlarged portions.

4. In a thermic telephone, a holder provided with through openings of uniform relatively small cross section at one end and of enlarged cross section at the other end, and a wire conductor having securing portions extending through said openings and a looped portion connecting those ends of said securing portions which are at the wide ends of said openings.

5. In a thermic telephone, a holder pro-

vided with through openings and with a transverse groove at one end of said openings, and a wire conductor extending through said openings and having bent ends seated in said groove, part of the conductor portion within said openings being provided with edges extending laterally beyond the

remainder of said portion and in firm engagement with the holder.

In testimony whereof, we have signed this 10 specification.

PIETER DE LANGE.
ROBERT AERNOUT BARON VAN LYNDEN.
